LEWIS J. ATWOOD, OF WATERBURY, CONNECTICUT.

Letters Patent No. 83,819, dated November 10, 1868.

IMPROVEMENT IN PIN-CUSHIONS.

The Schedule referred to in these Letters Patent and making part of the same.

To all whom it may concern:

Be it known that I, LEWIS J. ATWOOD, of Waterbury, in the county of New Haven, and State of Connecticut, have invented, made, and applied to use, a certain new and useful Improvement in Pin-Cushions; and I do hereby declare the following to be a full, clear, and exact description of the said invention, reference being had to the annexed drawing, making part of this specification, wherein—

Figure 1 is a side view of said cushion, and

Figure 2 is a section of said cushion.

Similar marks of reference denote the same parts.

Pin-cushions have been made with covered-paper sides, and a metallic rim perforated for the pins to be passed through; and circular and polygonal cushions have been made with a covering of woven material, sewed together around the edges.

The nature of my said invention consists in a pin-cushion, formed of a disk or ring of fibrous material, confined between two metallic disks, that are held together by rivets or similar metallic connections, so that a very strong, neat, cheap, and durable pin-cushion is formed, and one in which the sheet-metal disks may be used as an advertising-medium, by stamping upon them the desired name or address.

In the drawing, *a a* are sheet-metal disks, stamped up with concave or ring-shaped grooves around said

disks, near their edges, so that a circular opening shall be left around between the disks when they are set together, as at *b b*, fig. 2, and into this a coil of fibrous material, or a ring of felt, or similar material, *d*, is laid and securely confined.

The two disks are secured together by an eyelet, rivet, or similar fastening. I have shown a rivet, *c*.

Through the ring *d* the pins are stuck, the body-parts passing down between the disks *a a*, and if the pins are too long to go in straight, they can be stuck slightly inclined, so as to pass at the side of the rivet *c*.

The surface of the disk or disks is formed with names, numbers, or other devices, to indicate the business, address, or name, that it is desired to advertise or make known by means of the distribution of such cushions.

What I claim, and desire to secure by Letters Patent, is—

A pin-cushion, formed of a ring or disk of fibrous material, confined between two metallic plates that are connected together by rivets or other metallic connections, as set forth.

In witness whereof, I have hereunto set my signature, this 1st day of May, 1868.

L. J. ATWOOD.
